LID OR CLOSURE

Filed Dec. 30, 1929

FIG. 2.

Invention
Leon Benoit,
By Banning & Banning
J. L. B.

UNITED STATES PATENT OFFICE

LEON BENOIT, OF CHICAGO, ILLINOIS

LID OR CLOSURE

Application filed December 30, 1929. Serial No. 417,309.

This invention relates to lids or closures of a type which are suitable for hermetically sealing containers in which foodstuffs or other commodities may be placed.

5 The present improvements will be described in connection with closures of conventional type employed with glass containers, such as jelly glasses and the like. It will be understood that the invention is not intended to be limited to this particular closure 10 since it may be applied to any kind of closures which are normally stacked together for ease in handling. In practice such closures are closely nested and tend to adhere together, and difficulty is frequently encountered in 15 separating them in the operation of applying the closures to their several containers.

It is a primary object of my invention to provide a method of stacking such closures 20 so that adherence between them is positively prevented. The invention also comprises the resulting stack.

My invention further resides in the combination, construction and arrangements of 25 parts illustrated in the accompanying drawing, and while I have shown herein a preferred embodiment, I wish the same to be understood as illustrative only and not limiting the scope of my invention.

30 In the drawing,

Figure 1 is a sectional view through two adjacent, but separated, closures to which my invention may be applied.

Fig. 2 is an elevation of one of the closures 35 of Fig. 1 as seen from the underside,

Fig. 3 is a sectional view through a stack of closures of the forms shown in Fig. 1, and

Fig. 4 is a similar view of a stack made up from three modifications of the closures.

40 Referring to Figs 1 to 3 of the drawing, a series of closures 10 are formed from flat blanks which are pressed to provide channels 11 around their edges which commonly are turned to provide flanges, as shown. The 45 blank walls bordering these channels are commonly slanted or inclined to an extent which permits adjacent closures to nest in inter-fitting relation. These channels adherently receive a flexible sealing gasket 12 which is 50 usually of rubber or rubberlike material

which tends to be tacky particularly when new. It is the ordinary commercial practice to stack a large number of exactly similar closures such as 10 together, with the result that the exterior surfaces of the channels 55 11 come into contact with the tacky surfaces of the gaskets 12 of the superimposed closures so that the closures frequently adhere together and require to be separated by hand before they can be used. This adherence is 60 very objectionable, particularly where automatic machinery is employed for applying closures to containers.

In order to obviate this difficulty I provide a second series of closures 10', which are 65 similar to the closures 10. The closures 10 are provided with annular ribs 13 which are pressed up from their inner portions within the channels 11. The closures 10' are provided with similar ribs 13', which are of 70 different diameter from the annular ribs 13.

As shown in Fig. 3, I produce a stack of closures by superimposing, alternately, closures 10 and 10' until a stack of the desired 75 number is obtained. As will readily be seen in Fig. 3 the ribs 13 and 13' are unable to come into registry so that they serve as spacing projections which prevent close contact between adjacent closures which might result in their adherence together.

80 It will be understood that my invention may be modified in many ways. Thus, as shown in Fig. 4, I may employ three series of closures 14, 14' and 14'' which are similar except that they are provided with up-pressed annular ribs 15, 15' and 15'' which are of different diameters. These closures may be stacked regularly or irregularly, provided that each closure of one series is not in juxtaposition to another closure of the same series. 85 Obviously a greater number of series may be employed if desired.

90 It will be understood that the spacing projections are not necessarily of annular form. They may be constituted by other figures, ornamentation, trade-marks, or the like, provided that such figures or the like on any closure cannot be brought into register with the 95 deformations in the adjacent closures.

I claim:

1. A stack of closures comprising closures of a plurality of series in alternate relationship, each closure of a series being superposed and in juxtaposition to a closure of a different series, all the closures being provided with annular ribs spaced from the edges thereof, the diameter of the ribs being different in the closures of each series, whereby nesting of adjacent closures is prevented.

5 2. A stack of closures comprising closures of a plurality of series in alternate relationship, each closure of a series being superposed and in juxtaposition to a closure of a different series, all the closures being provided with 10 ribs spaced inwardly from the edges thereof, the arrangement of the ribs being different in the closures of each series, whereby nesting of adjacent closures is prevented.

15 20 In testimony whereof, I have hereunto set my hand this 26th day of December, 1929.

LEON BENOIT.
